UNITED STATES PATENT OFFICE.

CHARLES C. WICKWIRE, OF CORTLAND, NEW YORK, ASSIGNOR TO WICKWIRE
BROTHERS, OF CORTLAND, NEW YORK, A CORPORATION OF NEW YORK.

DESIGN FOR A WOVEN-WIRE FABRIC.

Application filed May 11, 1926. Serial No. 17,655. Term of patent 14 years.

To all whom it may concern:

Be it known that I, CHARLES C. WICKWIRE, a citizen of the United States, residing at Cortland, in the county of Cortland and State of New York, have invented a new, original, and ornamental Design for Woven-Wire Fabric, of which the following is a specification, reference being had to the accompanying drawing, forming part thereof.

The figure is a face view of a small section of a sheet of woven wire fabric, the design here shown being, in practice, repeated throughout the length of the sheet.

I claim:

The ornamental design for woven wire fabric, as shown and described.

CHARLES C. WICKWIRE.
